SIGNORS TO AKTIENGESELLSCHAFT BROWN BOVERI & CIE., OF BADEN, SWITZER-
LAND, A JOINT STOCK COMPANY OF SWITZERLAND.

INSULATOR MOUNTING.

Application filed August 22, 1927, Serial No. 214,512, and in Germany July 28, 1926.

This invention relates to insulator mountings, and it has among its objects an improved construction of an insulator and insulator bolt for suspending or mounting the 5 insulator:

According to the invention the pull between the insulator and its point of anchorage is transmitted by means of a simple bolt or pin having at its head two or more 10 projections or lugs which are inserted into longitudinal grooves in the recess within the insulator and then rotated about the axis of the bolt until the projections slide above the insulator ribs, separating the 15 grooves, and lock in this position.

The features of the invention will best appear from the following description of an exemplification thereof, reference being had to the accompanying drawings, wherein

20 Fig. 1 is a vertical section through a suspension insulator embodying one form of the invention;

Fig. 2 is a horizontal section through the insulator along lines II-II of Fig. 1; and

25 Fig. 3 is a similar view along lines III-III of Fig. 1.

Referring to the drawings, an insulator of the cap and pin type comprises a body of porcelain of familiar shape having a skirt 30 portion 1 and a head portion 2 in the form of a knob adapted to fit into a metal cap 3 into which the head may be cemented, as by means of a cement layer 4. The upper end of the cap 3 is provided with a perforated opening 5 for receiving the enlarged lower end 6 of a pin 7 suspended from an insulator above it.

The insulator head 2 has a central perforation 11 extending from the bottom surface thereof into the insulator head 2 and constituting at its upper end a cavity or chamber 12 within said head. The porcelain body around said central perforation 11 is provided with two or three longitudinal 45 grooves 13 which are arranged to permit passage of correspondingly shaped lateral projections or lugs 14 at the head of the pin 7 adapted to be inserted into the perforation 11 from the bottom opening thereof.

50 The cavity 12 within the insulator head is of hemispherical shape and the projections or lugs 14 are shaped to correspond to said hemispherical space and be rotated therein after having been placed therein through

the axial grooves 13. The pin 7 carries an 55 additional set of projections 15, preferably formed on a washer 16 secured to the pin, said washer projections 15 corresponding to the projections or lugs 14 on the head of the pin 7. The washer 16 with its projections is 60 so placed on said pin 7 as to be locked against rotation relative thereto and is placed at a suitable height, preferably immediately behind the opening of the perforation 11. Suitable slots or circumferential 65 grooves 18 within the ribs 19, separating the grooves 13 of the insulator, are arranged to receive the projections 15 of said washer when said projections are turned with the pin 7 within the perforation after insertion 70 thereof.

To mount the pin within the insulator, the pin is held so that the projections or lugs 14 are opposite the grooves 13 and the pin is moved upwardly until said projections 75 reach the cavity near the top of the porcelain head. The pin is thereupon rotated about 60 degrees until the projections 14 are opposite the ribs 19, separating the grooves, said ribs thus preventing said pin from 80 dropping down. This brings also the washer projections 15 into the circumferential grooves 18 at the lower portions of said ribs 19.

To hold the bolt in its final position the 85 grooves 13 may be filled with a suitable substance adapted to become hard, such as lead or cement. In the preferred construction wedges of metal, wood, fibre or like material are inserted into said grooves and suitably 90 cemented or locked therein. A flexible washer 21, for instance, of lead, may be placed between the lower surfaces of the head projections 14 and the upper surfaces of the ribs which carry said projections. 95 The wedges arranged to be inserted into the grooves 13, after locking the pin 7 in place, may also be flexible or elastic and arranged to lock in place so as to prevent their working loose.

100 A wedge of such construction is illustrated in the drawing wherein the lower portion of the wedge is split at 23 and biased so that on being inserted into the grooves the lower ends thereof will spread 105 and lock in a recess 24 at the corresponding point in the pin or in a similar recess 25 in the insulator wall, or in both. The use

of the wedge makes it possible to readily determine whether the pin has been correctly assembled and mounted within the insulator, because only when the upper projections 14 and the lower projections 15, carried by the pin, fit into their appropriate places along the ribs is it possible to insert the wedge 22 into the grooves 13.

Where a liquid filler or cement is used to hold the pin in place, a suitable mark is provided on an exposed portion of the pin near the lower end thereof. Such mark is, in general, however, not necessary in constructions utilizing the additional locking washer 16 with its projections 15, because as long as the pin is not in its appropriate angular position in which it is to be held, the washer projections 15 obstruct the flow of the sealing liquid or cement into the grooves if it is attempted to pour the same in place. Only if the head and washer projections are in their appropriate positions the grooves will be clear for introducing the sealing liquid thereto. Thus the washer 25 serves as an automatic check, making it impossible to pour in the sealing liquid until the pin is in correct position. It is, of course, possible to use both a liquid or cement filler and the spring wedge 22.

The invention is not limited to any particular detail of the construction or any particular type of insulator, and it is desired that the appended claims be construed broadly commensurate with the scope of the 35 invention within the art.

We claim as our invention:

1. In a pin type insulator, an insulator body of ceramic material, said body having a perforation extending from one side thereof into the interior of said body, the walls of said perforation having longitudinal grooves with ribs of said ceramic body extending between said grooves, said ribs ending in the interior of said body at a height below the end of said perforation to provide an enlarged cavity in the interior of said body, a mounting pin for said insulator having a shank portion projecting through said perforation into the interior of said insulator and a head portion comprising a plurality of laterally projecting lugs at the end of said shank portion, said lugs corresponding to said grooves and being adapted to be inserted therethrough with said pin from outside of said insulator body into said cavity and rotated therein to bear against the ends of said ribs within said cavity, and wedge members fitting said grooves for locking said head projections against lateral rotation.

2. In a pin type insulator, an insulator body of ceramic material, said body having a perforation extending from one side thereof into the interior of said body, the walls or said perforation having longitudinal

grooves with ribs of said ceramic body extending between said grooves, said ribs ending in the interior of said body at a height below the end of said perforation to provide an enlarged cavity in the interior of said body, a mounting pin for said insulator having a shank portion projecting through said perforation into the interior of said insulator, and a head portion comprising a plurality of laterally projecting lugs at the end of said shank portion, said lugs corresponding to said grooves and being adapted to be inserted therethrough with said pin from outside of said insulator body into said cavity and rotated therein to bear against the ends of said ribs within said cavity, wedge members fitting said grooves for locking said head projections against lateral rotation, and means on said wedge members for locking the same against longitudinal movement in said grooves.

3. In a pin type insulator, an insulator body of ceramic material, said body having a perforation extending from one side thereof into the interior of said body, the walls of said perforation having longitudinal grooves with ribs of said ceramic body extending between said grooves, said ribs ending in the interior of said body at a height below the end of said perforation to provide an enlarged cavity in the interior of said body, a mounting pin for said insulator having a shank portion projecting through said perforation into the interior of said insulator, and a head portion comprising a plurality of laterally projecting lugs at the end of said shank portion, said lugs corresponding to said grooves and being adapted to be inserted therethrough with said pin from outside of said insulator body into said cavity and rotated therein to bear against the ends of said ribs within said cavity, and wedge members fitting said grooves for locking said head projections against lateral rotation, said wedge members being of the spring type and said pin having recesses adapted to receive the projecting portions of said wedge members to prevent longitudinal movement thereof in said grooves on insertion thereof into the same.

4. In a pin type insulator, an insulator body of ceramic material, said body having a perforation extending from one side thereof into the interior of said body, the walls of said perforation having longitudinal grooves with ribs of said ceramic body extending between said grooves, said ribs ending in the interior of said body at a height below the end of said perforation to provide an enlarged cavity in the interior of said body, a mounting pin for said insulator having a shank portion projecting through said perforation into the interior of said insulator and a head portion comprising a plurality of laterally projecting lugs at the

end of said shank portion, said lugs corresponding to said grooves and being adapted to be inserted therethrough with said pin from outside of said insulator body into said 5 cavity and rotated therein to bear against the ends of said ribs within said cavity, and a second set of projections on said pin corresponding to the projections on said head, said second set of projections being near the 10 entrance into said perforation.

5. In a pin type insulator, an insulator body of ceramic material, said body having a perforation extending from one side thereof into the interior of said body, the walls of 15 said perforation having longitudinal grooves with ribs of said ceramic body extending between said grooves, said ribs ending in the interior of said body at a height below the end of said perforation to provide an enlarged cavity in the interior of said body, a mounting pin for said insulator having a shank portion projecting through said 20 perforation into the interior of said insulator and a head portion comprising a plurality of laterally projecting lugs at the end of said shank portion, said lugs corresponding to said grooves and being adapted to be 25 inserted therethrough with said pin from outside of said insulator body into said cavity and rotated therein to bear against the ends of said ribs within said cavity, means for locking said pin in position against rotation thereof within said perforation, and a second set of projections on said pin 30 fixedly aligned with the projections on said head, said second set of projections being

disposed near the entrance of said perforation.

6. In a pin type insulator, an insulator body of ceramic material, said body having 40 a perforation extending from one side thereof into the interior of said body, the walls of said perforation having longitudinal grooves with ribs of said ceramic body extending between said grooves, said ribs ending in the interior of said body at a height below the end of said perforation to provide an enlarged cavity in the interior of said body, a mounting pin for said insulator having a shank portion projecting through said 45 perforation into the interior of said insulator and a head portion comprising a plurality of laterally projecting lugs at the end of said shank portion, said lugs corresponding to said grooves and being adapted to be 50 inserted therethrough with said pin from outside of said insulator body into said cavity and rotated therein to bear against the ends of said ribs within said cavity, wedge members fitting said grooves for 55 locking said head projections against lateral rotation, and a second set of projections on said pin corresponding to the projections on said head, said second set of projections being near the entrance into said perforation. 60

In testimony whereof we have hereunto subscribed our names this 5th day of July A. D., 1927, at Stuttgart, Germany.

B. KATZENBERGER.
TH. JANSEN.
